Primary Examiner — Paula Greene

(57) **CLAIM**

We claim the ornamental design for a subwoofer display support, as shown and described.

DESCRIPTION

FIG. 1 is a front perspective view of a subwoofer display support supporting a keyboard;
FIG. 2 is a front view thereof;
FIG. 3 is a rear view thereof;
FIG. 4 is a top view thereof;
FIG. 5 is a left side view thereof;
FIG. 6 is a right side view thereof;
FIG. 7 is a front perspective view of the subwoofer display support supporting a display; and,
FIG. 8 is a right side view of the sub over display support supporting the display.

The dash-dash broken lines in the drawings are environmental lines which do not form part of the claimed design. The short dash-long dash lines are boundary lines which do not form part of the claimed design.

1 Claim, 8 Drawing Sheets
